UNITED STATES PATENT OFFICE.

LOUIS SCHWARTZBERG, OF CHICAGO, ILLINOIS.

CELLULAR CARTON.

Application filed January 26, 1923. Serial No. 614,988.

To all whom it may concern:

Be it known that I, LOUIS SCHWARTZBERG, a citizen of the United States, residing at Chicago, in the county of Cook and State of Illinois, have invented a new and useful Improvement in a Cellular Carton, of which the following is a specification.

My present invention relates to cartons and similar receptacles, and more particularly to a structure of this character that is usually employed in connection with the packaging of eggs for the retail market.

One of the objects of my invention is the provision of a carton having a cellular interior so that the eggs or other articles placed therein will be separated from each other, and may be conveniently handled or dispensed, a dozen to a package as is the usual practice in groceries, markets, etc.

Another object is the provision of a carton that is fabricated preferably from a single piece of material so that the blanks which are to be folded and formed into the cartons may be rapidly made in large quantities and may be conveniently stored in flat condition prior to assembly. A still further object resides in the provision of a cellular carton that may be collapsed or folded flat prior to being used for the dispensing of the articles so that a large quantity of the assembled structures may be collapsed and packed away in a relative small space for both shipment and storage. In this connection, I have provided means for simultaneously moving all the transverse cell walls to their vertical positions and for maintaining them in such position while the carton is in use. I have also provided end walls that are hinged to one of the body walls of the assembled carton that are adapted to be moved to a position in a vertical plane transverse to the plane of the body walls and there engaged with elements projecting from one of the opposite longitudinal walls to maintain said end walls against lateral movement outside the dimensions of the carton body while in use. Other objects reside in providing a carton of the character above described that is novel and dependable in construction; is comparatively cheap to manufacture so that it may be sold for a moderate price, and which is easy to manipulate to open or collapse. Numerous other objects and advantages will be apparent to others after an understanding of my invention is had, and I prefer to carry out my invention in sub-

stantially the manner hereinafter described, and as more particularly pointed out in the claims.

Reference will now be made to the accompanying drawings that form a part of this specification, in which—

Fig. 1 is a perspective of my carton, with the cover unlocked and raised to disclose the interior construction when in use.

Fig. 2 is a plan of the blank employed in forming the carton.

Fig. 3 is a longitudinal vertical section at one end of the carton showing the manner of collapsing the transverse end and cell walls.

Fig. 4 is a longitudinal vertical section at the opposite end of the carton showing the manner of maintaining the transverse cell walls and the adjacent end wall in position.

Fig. 5 is a fragmentary perspective of the right hand end of the carton shown in Figs. 1 and 4.

Fig. 6 is a fragmentary perspective of the left hand end of the carton showing it in collapsed position.

Fig. 7 is a fragmentary top view showing a modified construction of the top wall.

Figs. 8 to 12 illustrate, schematically, the left hand ends of cartons of different assemblies, showing divers modes of folding the blank for forming the body or outside walls, the dividing partitions and the cover, and several methods of assembling the same.

The drawings illustrate typical embodiments of my invention, and by referring to Fig. 1, which is the preferred form, it will be seen the body of the carton, when opened and ready for use, comprises longitudinally elongated vertical front and rear walls A and B, respectively; a bottom C connecting the lower edges thereof, and a top member or wall D connecting the upper edges of said front and rear walls. Extending from back wall B is a cover E that is hinged thereto by forming a score or bend e at the juncture between the members so that the cover may be folded down above top wall D of the body in the usual manner of cellular egg cartons. Extending along the front longitudinal edge of the cover is an extension or flap F that is folded down or laterally to the cover, and from the outer edge of which project hook shaped locking members f that are adapted, when the cover is lowered into position to close

the carton, to engage coacting portions of top wall D, as will hereinafter more fully appear.

Formed integrally with top wall D, in the preferred structure, is a center partition G that is formed from intermediate portions of the top wall and is made by first providing upturned flanges 15 at the center of width of the top wall portion of the blank and then bending the material between these flanges downwardly to provide parallel pieces 16 extending downwardly to bottom C. If desired, however, partition G may be a separate piece of material G', as illustrated in Figs. 10 and 12 of the drawings, the upper edge thereof being inserted in the channel formed by the upwardly extending flanges 15 of the top or wall D, and secured thereto in any suitable manner, preferably by staples, or cement; or the said partition may be formed integrally with bottom C by folding upwardly an intermediate portion G² of the bottom wall portion of the blank as illustrated in Fig. 11 of the drawings, in which latter event the lower portion of pieces G² may be secured together adjacent bottom wall C and the upper edge is inserted in a groove or channel formed by flanges 15 in the top wall, similar to the structure shown in Figs. 10 and 12. The partition G extends longitudinally of the body of the carton so as to divide the interior into two similarly shaped side by side longitudinal compartments, one to the front and one to the rear, and said partition, when in vertical position, or transverse to the top and bottom walls, stiffens the structure and assists in maintaining the rectangular or boxlike form of the carton. The transverse walls that divide the interior of the carton into cells are formed by making irregularly shaped cuts in the blank upon each side of flanges 15 and extending to, respectively, the front and rear walls so that suitable flaps 17 are provided that are adapted to be moved down to approximately the bottom C and thus divide the longitudinal compartments into substantially cube shaped cells, arranged in longitudinal rows upon each side of central partition G. The cuts to form these cell walls or flaps 17 are, preferably of octagonal shape upon the left hand half so that triangular shaped corner connections 18 remain in the top wall when the cell walls have been moved downwardly into position, and the diagonal or oblique edges of these corner pieces 18 at front of the carton, connect the cell walls with the adjacent body wall A, and at the front of the carton these corner pieces provide means for engaging hooks f on the locking flange of the cover when the latter is lowered into position for closing the carton.

As seen in Figs. 3 and 4, I connect the lower portions of cell walls or flaps 17 by a pull-string 19, the end or looped portion 20

of which, when the cell walls have been drawn to their vertical position, is slipped over the adjacent or right hand end of flanges 15 that extend above the top wall, as seen in Figs. 4 and 5. The ends walls 21 of the carton are provided by utilizing the cell walls at the right hand end, and in this connection, I form extensions 22 from bottom C that are folded over upon said bottom member at the right hand end, which extensions have upstanding flanges 23 that provide means against which the lower portion of the end cell wall 21 will engage and thereby prevent its being forced out of the carton and cause the loss of the egg, or other article in the end cell. When the carton is collapsed, in the manner shown in Fig. 6, this end cell wall 21 will fold up into the opening in the top wall from which cell wall 21 is formed, and the upstanding piece 32 is folded flat down upon the bottom.

The left hand end walls of the carton are formed by providing rectangular extensions upon top member D of the blank which have inwardly folded portions 24 that engage the under surfaces of top wall D on each side of the partition and from which the rectangular shaped end walls 25 depend. Lateral flaps or flanges 26 are provided along the edges of walls 25 adjacent the rear or back wall B and the central partition wall G, which flanges are secured to their respective longitudinal walls in any suitable manner, by pasting, stapling or otherwise. These end walls 25 are provided each with a diagonal fold 27 extending from the upper rear corner to the lower front corner, as seen in Fig. 1, and in dotted lines in Fig. 2 so that when the carton is collapsed these end walls 25 at the left hand end of the carton may be bent outwardly along the diagonal folds 27 in the manner shown in Figs. 3 and 6 of the drawings, so that top wall D and front wall A will be disposed substantially flat adjacent the back and bottom walls, as shown in Fig. 6.

In order to provide means for retaining eggs of different sizes in the carton, I may provide the diagonal portions of triangular pieces 18 heretofore mentioned with semicircular serrations 28 that extend into the upper portions of the individual cells so that when a small egg is inserted into a cell the upper portions will engage the outer edges of the serrations, but when an egg of large diameter is inserted the serrations will bend over, more or less, downwardly so that the remaining edges of the diagonal or triangular corner pieces will engage the upper portion of the egg and maintain it in position.

As seen in Figs. 8 to 12, top E may be formed either as a continuation of the back or rear wall B, as seen in Figs. 8 to 11, or it may be formed from the upstanding portion

D of the top wall, in which event wall B is extended upwardly to the height of partition G or G' and upstanding portion D' is secured adjacent the upper edge of the back wall. Also it will be noted from the above mentioned figures that top wall D may be secured to the cover or to the back wall, or may have a depending extension D² that terminates at its lower edge in a lateral piece D³ 10 that extends along the adjacent portion of bottom C, as illustrated in Fig. 9 of the drawings, and is secured thereto in any suitable manner. In this latter event, it is unnecessary to secure back wall B to the depending extension D² unless so desired.

It is obvious that many other modifications of my invention may be made without departing from the principles of my invention as embodied in the appended claims, 20 and I therefore desire it understood that all such changes are fully contemplated as coming within the scope of said claims.

What I claim is:

1. A collapsible carton comprising vertical front and rear walls, spaced horizontal walls connecting, respectively, the upper and lower portions of said vertical walls, a longitudinal partition directly connected to one of said horizontal walls and extended to the opposite wall, and cell walls formed with and depressed from the upper horizontal wall upon opposite sides of said partition whereby a plurality of rows of cells are provided in the body of the carton, the construction and arrangement of the elements being such as to permit collapsing of the carton.

2. A collapsible carton comprising vertical front and rear walls, horizontal walls connecting, respectively, the upper and lower portions of said vertical walls, a longitudinal partition directly connected to one of said horizontal walls and extended to the opposite wall, and transverse cell walls formed with and depressed from the top wall upon each side of said partition, the construction and arrangement of the elements being such as to permit collapsing of the carton.

3. A collapsible carton comprising front and rear walls, top and bottom walls connecting the respective portions of said front and rear walls, a longitudinal partition formed integrally with said top wall, and transverse cell walls formed integrally with and depressed from said top wall upon each side of said partition, the construction and arrangement of the elements being such as to permit collapsing of the carton.

4. A cell carton comprising vertical front and rear walls, horizontal walls connecting respectively, the upper and lower portions of said vertical walls, transverse cell walls formed integrally from one of said horizontal walls, and means connecting the ends of said cell walls opposite their attachment to the horizontal wall whereby said walls are

maintained in their relative normal positions and the release of said means will permit the disposition of said cell walls in the same horizontal plane and thereby collapse the carton into a flat position.

5. A cell carton comprising vertical front and rear walls, horizontal walls connecting, respectively, the upper and lower portions of said vertical walls, transverse cell walls formed integrally from one of said horizontal walls, and flexible means connecting the ends of said cell walls opposite their attachment to the horizontal wall whereby said walls are maintained in their relative normal positions and the release of said means will permit the disposition of said cell walls in the same horizontal plane thereby collapse the carton into a flat position.

6. A cell carton comprising vertical front and rear walls, top and bottom walls connecting the respective portions of said vertical walls, transverse cell walls formed integrally from said top wall and folded down into said carton, and means connecting the lower ends of said cell walls whereby said latter walls are maintained in vertical position and the release of said means will permit the collapsing of the carton into a flat position.

7. A cell carton comprising vertical front and rear walls, top and bottom walls, connecting the respective portions of said vertical walls, transverse cell walls formed integrally from said top wall and folded down into said carton, and a flexible draw-cord connecting the lower ends of said cell walls whereby said latter walls are maintained in vertical position and the release of said draw-cord will permit the collapsing of the carton into a flat position.

8. A cell carton comprising vertical front and rear walls, horizontal walls connecting, respectively, the upper and lower portions of said vertical walls, a longitudinal partition connected to one of said horizontal walls and extended to the opposite wall, transverse cell walls formed integrally from one of said horizontal walls upon opposite sides of the plane of said partition wall, and means connecting the ends of said cell walls opposite their attachment to the horizontal wall; said means coacting with said partition to maintain said cell walls in their relative normal positions and the release of said means will permit the collapsing of the carton into a flat position.

9. A cell carton comprising vertical front and rear walls, horizontal walls connecting, respectively, the upper and lower portions of said vertical walls, a longitudinal partition connected to one of said horizontal walls and extended to the opposite wall, transverse cell walls formed integrally from one of said horizontal walls upon opposite sides of the plane of said partition wall, and

- a flexible draw-cord connecting the ends of said cell walls opposite their attachment to the horizontal wall; said draw-cord coacting with said partition to maintain said cell walls in their relative normal positions and the release of said draw-cord will permit the collapsing of the carton into a flat position.
10. A cell carton comprising vertical front and rear walls, horizontal walls connecting, respectively, the upper and lower portions of said vertical walls, a longitudinal partition formed from one of said horizontal walls by folding said wall upon itself intermediate its longitudinal edges and toward the opposite horizontal wall, and transverse cell walls upon opposite sides of said partition, whereby a plurality of cells are provided within the body of the carton, the construction and arrangement of the elements being such as to permit collapsing of the carton.
11. A cell carton comprising vertical front and rear walls, top and bottom walls connecting the respective portions thereof, a longitudinal partition formed from said top wall by folding the same upon itself intermediate its longitudinal edges and towards the bottom wall, and transverse cell walls formed from said top wall upon opposite sides of said partition, whereby a plurality of cells are provided within the body of the carton, the construction and arrangement of the elements being such as to permit collapsing of the carton.
12. A carton comprising three longitudinally disposed vertical walls providing, respectively the front and rear walls of the carton and a dividing partition therefor, horizontally disposed walls connecting the upper and lower portions of said front and rear walls and coacting with said partition, and an end wall connected to certain of the aforesaid walls on each side of said partition each end wall having an oblique fold extending from an upper corner to a diagonally opposite lower corner, whereby both of said end walls may be bent laterally along said folds when said carton is collapsed.
13. A carton comprising front and rear walls, top and bottom walls connecting the same, a plurality of transverse cell-walls formed from said top wall so as to be swung down laterally thereto, and a stop extending upwardly a short distance from the bottom at the end of the carton against which the end cell wall engages, said stops being foldable flat against the bottom wall when the carton is collapsed.
14. A carton comprising front and rear walls, top and bottom walls connecting the same, a longitudinal intermediate wall dividing the carton into two side-by-side longitudinal chambers, a plurality of transverse cell-walls formed from said top wall upon each side of said intermediate wall so as to be swung laterally to said top wall, and stops extending upwardly a short distance from the bottom at the end of the carton against which the end cell walls engage, said stops being foldable flat against the bottom wall when the carton is collapsed.
15. A carton comprising front and rear walls, top and bottom walls connecting the same, a plurality of transverse cell walls formed from said top wall so as to be swung down laterally thereto, and stops extending upwardly a short distance from the bottom wall upon each side of said intermediate wall against which the lower portion of the end cell-wall engages, said stops being foldable flat against the bottom wall when the carton is collapsed.
16. A carton comprising front and rear walls, top and bottom walls connecting the same, a longitudinal intermediate wall dividing the carton into two side by side longitudinal chambers, a plurality of transverse cell walls formed from said top wall upon each side of said intermediate wall so as to be swung laterally to said top wall, and stops extending upwardly a short distance from the bottom wall upon each side of said intermediate wall against which the lower portions of the end cell walls engage, said stops being foldable flat against the bottom wall when the carton is collapsed.
17. In a carton having a hollow body, a plurality of hinged cell walls, and means connecting the ends of said walls opposite their hinges whereby said walls are maintained in normal positions and the longitudinal movement of said means will collapse said walls.
18. In a carton having a hollow body, a longitudinal partition, a plurality of hinged cell walls arranged upon opposite sides of said partition, and a pull cord looped intermediate its ends and connecting the ends of said walls opposite their hinges whereby said walls may be simultaneously moved to their normal positions the loop in said pull cord being engageable with the partition for maintaining the cell walls in position.
19. In a carton having a hollow body and a longitudinal partition, a row of cell walls hinged to a body wall upon each side of said partition, and means common to all cell walls for maintaining the same in normal positions and the longitudinal movement of said means will collapse said walls.

Signed at Chicago, county of Cook and State of Illinois, this 20th day of January, 1923.

LOUIS SCHWARTZBERG.
